UNITED STATES PATENT OFFICE.

EDWARD Z. COLLINGS, OF CAMDEN, NEW JERSEY, AND CHARLES F. PIKE,
OF PHILADELPHIA, PENNSYLVANIA.

REFRIGERATOR.

SPECIFICATION forming part of Letters Patent No. 311,813, dated February 3, 1825.

Application filed May 15, 1824. (No model.)

To all whom it may concern:

Be it known that we, EDWARD Z. COLLINGS, residing at Camden, in the county of Camden and State of New Jersey, and CHARLES F. PIKE, residing at Philadelphia, in the county of Philadelphia and State of Pennsylvania, citizens of the United States, have invented 5 certain new and useful Improvements in Refrigerators, of which the following is a specification, reference being had therein to the accompanying drawings, wherein—

Figure 1 is a longitudinal vertical section of a refrigerator embodying our improvements. Fig. 2 is a broken elevation illustrating a modification, and Figs. 3 and 4 are detail sections of modified forms of pans or troughs for the refrigerator.

Our invention has relation to that form of refrigerator provided with an ice-box and a series of pans or troughs for conducting the drip from the ice-box through and out of the refrigerator, and it has for its object to increase the efficiency of the drip, or cause it to produce greater refrigerant results.

25 Our invention accordingly consists of the combination, construction, and arrangement of parts, as hereinafter described and claimed.

In the drawings, A represents a refrigerator-box, which may be portable or stationary 30 and of any suitable construction and configuration. It is provided with a lid, a, and an ice-box, a', having a drip-outlet, a''.

B B represent a series of pans of any construction in cross-section. They may be of 35 uneven lengths, as shown, increasing from above downwardly, or they may all be of the same size, and are secured in position in any suitable manner. Each pan is provided with a siphon outlet or pipe, b, which may be a bent pipe, as indicated in Fig. 1, or formed as represented in Figs. 3 and 4. The pans or troughs B may be longitudinally parallel or inclined, as shown in Fig. 4.

The operation is obvious. The drip from 45 ice-box a' falls into the first pan of the series B, and accumulates therein until its level rises above and forces the air from or creates a vacuum in bent pipe b, to start it siphoning. Such drip is then siphoned from said first 50 pan into the succeeding pan, and this, being larger than the former, detains the drip there-

in until additional drip is supplied thereto to start the siphonage. As soon as this takes place the drip in the second pan passes into the third pan, and so on until it finds its exit 55 from box A. The drip, it will be noted, is detained in each pan for a certain length of time, so that its passage or flow through box A is slow or intermittent, and the full benefit of its reduced temperature is obtained, as 60 much as it is possible to do so, to effect the best refrigerant results in box A.

Instead of using fixed pans and siphon outlets or pipes, as above described, the latter may be dispensed with and the pans pivoted, 65 as indicated in Fig. 2, so that when a given quantity or volume of water accumulates therein they will tilt upon their pivotal points and empty themselves and return to their normal position by gravity or under the 70 influence of a spring.

While we have shown and described two forms of pans for effecting an intermittent flow of drip through the refrigerator-box A, yet we do not wish to be understood as limiting 75 ourselves thereto, as it is obvious that the construction, arrangement of the pans, and the operation of emptying them to produce the intermittent flow may be varied without departing from the spirit of our invention. It 80 will be noticed that the drip from the ice-box is continuous as long as the latter is supplied with ice, and that the flow of the drip is intermittent through the pans B.

Instead of using drip from the ice in box 85 a', it may be filled with or have a supply of refrigerant liquid.

What we claim is—

1. A refrigerator having an ice-box provided with a drip-outlet and a series of pans 90 or troughs communicating with one another, and providing an intermittent passage or flow for the drip, substantially as shown and described.

2. A refrigerator having an ice-box with 95 drip-outlet and a series of pans or troughs which successively receive the drip and automatically and intermittently discharge it, substantially as shown and described.

3. A refrigerator having an ice-box with 100 drip-outlet and a series of communicating pans or troughs adapted to receive and detain

the drip therein and automatically and intermittently discharge it therefrom, substantially as shown and described.

4. A refrigerator having an ice - box with drip - outlet and a series of communicating pans or troughs of gradually-increasing size, adapted to receive, detain, and automatically and intermittently discharge the drip, substantially as shown and described.

10 5. A refrigerator provided with a supply of refrigerant liquid or drip, and a series of communicating pans or troughs adapted to receive and detain such liquid therein and automatically and intermittently discharge it therefrom, substantially as shown and described.

15 6. The method herein described for producing the refrigerant results in refrigerators, which consists of passing an intermittent flow 20 of refrigerant liquid through the refrigerator, substantially as shown and described.

7. A refrigerator having an ice - box with drip-outlet and a series of pans or troughs having siphon - outlets which intermittently draw the water from the pans, substantially 25 as shown and described.

8. A refrigerator having ice - box a' , drip-outlet a'' , and pans B, of different sizes, and provided with siphon - outlets, said siphons intermittently drawing the water from the 30 pans, substantially as shown and described.

9. A refrigerator having a continuous drip or flow from the ice-box and an intermittent flow for said drip through the refrigerator-box, substantially as shown and described. 35

In testimony whereof we affix our signatures in presence of two witnesses.

EDWARD Z. COLLINGS.
CHAS. F. PIKE.
